UNITED STATES PATENT OFFICE.

ISIDOR HERMANN, OF NEW YORK, N. Y., ASSIGNOR TO ROSALIE HERMANN,
OF SAME PLACE.

DESIGN FOR A HOOD.

SPECIFICATION forming part of Design No. 16,933, dated October 12, 1886.

Application filed June 16, 1886. Serial No. 205,382. Term of patent 3½ years.

To all whom it may concern:

Be it known that I, ISIDOR HERMANN, of the city, county, and State of New York, have invented a new and original Design for Hoods, of which the following is a specification.

The nature of my design is fully represented in the accompanying drawing, in which a perspective view of my design for hoods is shown.

The leading feature of my design consists in a cap or hood having an opening at the front and bottom, and having the tip or point returned to the upper front side limb of the crown.

A is a hood having openings at the front and bottom. B is a border along the edges of the openings, said border having a fuzzy surface. C is a button, and D is a tassel at the point of the hood, which point is returned to the upper front side limb of the crown.

Having thus described my design, I claim as new and desire to secure by Letters Patent—

1. The design for a hood, substantially as herein shown and described, the same consisting of a hood having a front and bottom opening, and the tip or point of the hood returned to the upper front side limb of the crown.

2. The design for a hood, substantially as

herein shown and described, the same consisting of a hood having front and bottom openings, a fuzzy border along the edges of the openings, and the point or tip of the hood returned to the upper front side limb of the crown.

3. The design for a hood, substantially as herein shown and described, the same consisting of a hood having front and bottom openings, and the tip or point returned to the upper front side limb of the crown, and the button C.

4. The design for a hood, substantially as herein shown and described, the same consisting of a hood having front and bottom openings, a fuzzy border along the edges of the openings, and the point or tip of the hood returned to the upper front side limb of the crown, the button C, and the tassel D.

In testimony that I claim the foregoing as my invention I have signed my name in presence of two subscribing witnesses.

ISIDOR HERMANN.

Witnesses:

PAUL GOEPEL,
MARTIN PETRY.
